METHOD AND APPARATUS FOR FORMING "F" OBLONG CAN BODIES

George M. Flynn, Chicago, Ill., assignor to Continental Can Company, Inc., New York, N.Y., a corporation of New York

Filed Apr. 8, 1963, Ser. No. 271,252
35 Claims. (Cl. 72—210)

This invention provides a novel method and apparatus for reforming or deforming tubular resilient bodies to form bodies for "F" style cans.

The bodies for "F" style cans are rectangular in cross section, have rounded corners, and are commonly formed on a mandrel or horn of a body making machine, such as the can body maker disclosed in United States Patent 2,429,169 to Paul E. Pearson, et al.

A vertical end or sectional view of the mandrel or horn has an hour-glass contour and forming wings of the body-making machine wrap a can body-blank around the mandrel until it conforms to the hour-glass contour thereof, at which time the side seam of the can body is completed.

When the forming wings are reopened, the completed can body is pushed off the forming mandrel. However, the sides of the can body may not retain the hour-glass contour of the mandrel but recover to an objectionable slightly convexed curvature. Subsequent end seaming operations which connect the can-ends to the can body tend to flatten the sides of the can body, but fail to completely flatten the sides.

While the hour-glass contour of the mandrel permits the rounded corners of the can bodies to be bent excessively during formation to compensate for the above-mentioned recovery of the can bodies, this method of compensating for spring-back recovery is limited by the width of the mandrel. That is, a mandrel can only be "necked-in" a certain amount, and this amount is insufficient to preclude the spring-back of a can body to a slightly convex curvature. This is particularly true in the forming of "F" style can bodies from highly tempered, light-weight tinplate.

In the development of lighter weight tinplate for use in making "F" style can bodies, it has been found necessary to increase the temper of the tinplate when the thickness thereof is decreased in order to sufficiently strengthen the thinner tinplate. However, existing mandrels or horns frequently cannot be used for making "F" style cans from a thinner, highly tempered tinplate because the concavities forming the hour-glass contoured mandrel cannot be concavely increased in curvature an amount sufficient to compensate for the recovery characteristics of highly tempered tinplate. In other words, an increase in the temper of the tinplate cause the side of an "F" style can body formed on a conventional mandrel to return to an objectionable convexly curved contour approaching an ellipse when the can body is removed from the mandrel.

The present invention overcomes the above-mentioned objectionable convexly-curved "F" style can bodies by providing a novel method which may include an initial step of forming a relatively thin and highly tempered can body-blank on a conventional round or hour-glass mandrel of a body making machine to an ellipsoidal shape of the character above-described. Subsequently, these elliptical bodies are transported between a plurality of guiding and forming rollers which overbend the bodies by exteriorly applied forces which reform the bodies to an hour-glass contour. Upon removal of the bodies from between the guiding and forming rollers, the spring-back recovery of the bodies causes the same to return to a

2

rectangular cross-sectional outline. This overbending of can bodies beyond a point which precludes the recovery of the bodies to a convexly curved contour is achieved by a novel apparatus, devoid of mandrels or other such similar internal shaping mechanisms which prevent optimum overbending of can bodies, for reforming the bodies by applying forces to only exterior portions of the can bodies.

Therefore, an object of this invention is to provide a novel method and apparatus for reforming tubular resilient can bodies by overbending the bodies to compensate for the spring-back recovery characteristics thereof whereby polygonal shaped "F" style can bodies are formed.

10 15 Another object of this invention is to provide a novel apparatus for forming "F" style can bodies from lighter weight, higher tempered tinplate than heretofore possible by conventional forming apparatus.

20 25 A further object of this invention is the provision of a novel deforming or reforming mechanism which includes a plurality of cooperative convexly contoured guiding and forming rollers which are arranged to form a generally hour-glass opening through which can bodies are transported and exteriorly deformed.

30 35 Still another object of this invention is the provision of a novel deforming or reforming mechanism which includes a plurality of convexly contoured guiding and forming rollers and a plurality of conveyor belts cooperative therewith for transporting can bodies through the guiding and forming rollers.

35 40 Still another object of this invention is to provide a novel longitudinally extending, axially accessible reforming mechanism including a transport mechanism for establishing a predetermined path of travel for can-bodies through the longitudinally extending member, and wherein in the longitudinally extending member is provided with a plurality of guide-forming means having opposed convexly curved surfaces, the curvature of which progressively increases along the length of the longitudinally extending member to define a converging path of travel for the can-bodies.

45 50 Still another object of this invention is the provision of a novel longitudinally extending axially open guide-forming apparatus consisting of a plurality of converging rods arranged in a generally hour-glass configuration around a transport mechanism for solely outwardly concavely indenting can-bodies while the same are being transported through the guide-forming mechanism.

55 60 Still another object of this invention is the provision of a novel longitudinally extending axially open guide-forming apparatus consisting of a peripherally closed elongated tapered tubular member of a generally hour-glass configuration around a transport mechanism for solely outwardly concavely indenting can-bodies while the same are being transported through the guide-forming mechanism.

65 70 Still another object of this invention is the provision of a novel apparatus for deforming or reforming longitudinal edges of resilient tubular can bodies by providing a plurality of opposed concavely curved rollers disposed on opposite sides of a transport mechanism and arranged thereabout to deform the longitudinal edges of the can bodies transported therebetween to a generally hour-glass cross-sectional configuration.

75 Another object of this invention is to provide deforming or reforming mechanism of the character above described which includes a transport mechanism cooperative with each of the plurality of guiding and forming rollers to transport can-bodies therebetween.

Still another object of this invention is to provide a novel method of producing "F" style can bodies by in-

denting opposite sides of a tubular body, terminating this indenting, and subsequently releasing and permitting the indented portions to reshape themselves to form a flat sided "F" style can body.

With the above and other objects in view that will hereinafter appear, the nature of the invention will be more clearly understood by a reference to the following detailed description, the appended claims and the several views illustrated in the accompanying drawings.

In the drawings:

FIGURE 1 is a top perspective view with parts broken away, and illustrates a reforming apparatus constructed in accordance with this invention including a plurality of convexly curved opposed rollers disposed on opposite sides of a converging longitudinally extending axially open path, a plurality of opposed concavely curved longitudinal edge rollers, and a plurality of opposed conveyor belts for transporting can-bodies along the converging path.

FIGURE 2 is an enlarged fragmentary vertical sectional view taken along the line 2-2 of FIGURE 1, and shows the differences in curvature of the plurality of convexly curved opposed rollers, and the opposed concavely curved longitudinal edge rollers.

FIGURE 3 is a cross-sectional view taken along line 3-3 of FIGURE 2, and illustrates a generally hour-glass contoured opening enclosed by the convexly curved rollers and the concavely curved longitudinal edge rollers, and a can body, in phantom lines, within the opening.

FIGURE 4 is a transverse fragmentary sectional view taken along line 4-4 of FIGURE 1, and additionally illustrates the relationship of the plurality of convexly curved opposed rollers.

FIGURE 5 is a vertical sectional view taken along line 5-5 of FIGURE 2, and illustrates one of two pair of rollers cooperatively driving an upper conveyor belt run of one of the plurality of opposed conveyor belts.

FIGURE 6 is a vertical sectional view of a modified reforming apparatus, similar to the reforming apparatus illustrated in FIGURES 1-4, and shows two pair of opposed concavely curved rollers which exteriorly deform only the longitudinal edges of a can body to reform the same to a hour-glass contour.

FIGURE 7 is an end perspective view of a modified reforming apparatus, similar to the apparatus illustrated in FIGURES 1-4 and 6, and illustrates a plurality of longitudinally extending rods arranged in a generally hour-glass cross-sectional configuration.

FIGURE 8 is a cross-sectional view of a "F" style can body formed by any one of the reforming mechanisms illustrated in FIGURES 1-7, and clearly illustrates in phantom lines the hour-glass contour of the can body immediately before removal of the can body from any one of the reforming mechanisms of FIGURES 1-7.

A deforming or reforming apparatus constructed in accordance with this invention for forming "F" style can-bodies is illustrated in FIGURES 1-4 of the drawings, and is generally designated by reference numeral 10. The reforming or deforming apparatus 10 includes a plurality of longitudinally spaced and axially aligned guide-forming means 11, 12 and 13. The guide-forming means 11, 12 and 13 are maintained in spaced relation and axial alignment by a plurality of longitudinally extending supports 14. Each of the guide-forming means 11, 12 and 13 is fixedly secured to each of the supports 14 by suitable means (not shown), such as screws or by welding.

Each of the plurality of guide-forming means 11, 12 and 13 includes a guide block 15. Since each of the guide blocks 15 are substantially similar, a description of the guide block 15 of the guide-forming means 11 is considered sufficient for a complete understanding of the invention. As is best illustrated in FIGURE 1, each of the guide blocks 15 includes a generally cross-shaped

opening 16. The opening 16 decreases in height and width from left to right as is best illustrated in FIGURE 2 to define a generally converging open path through the reforming apparatus 10.

The cross-shaped opening 16 of FIGURE 3 includes an upper, downwardly opening portion 17 and a lower, upwardly opening portion 18. Inwardly opening opposed portions 20 and 21 form the "arms" of the cross-shaped openings 16. The downwardly opening portion 17 and the upwardly opening portion 18 are each traversed by an identical threaded bolt 22 inserted through access apertures 23 in the guide block 15. A threaded end 24 of each of the bolts 22 is threadably secured in a threaded aperture 25 in axial alignment with each of the access apertures 23, as is clearly shown in FIGURE 3. The inwardly opening portions 20 and 21 are similarly traversed by a threaded bolt 26 inserted through each of two access apertures 27. Identical threaded ends 28 of the bolts 26 are each received in a threaded aperture 30 in axial alignment with its associated access aperture 27. It should be noted that each of the threaded apertures 25 open into the access apertures 27, while the threaded apertures 30, 30 open into each of the access apertures 23. This construction allows the ends 24 of the bolts 22 to bear against the bolts 26 to additionally secure the bolts 26 in the guide block 15. The bolts 22 are similarly securely maintained within the guide block 15 by the abutting ends 28 of the bolts 26.

As is best illustrated in FIGURES 1 and 2 of the drawings, one set or stand of opposed convexly curved guiding and forming rollers 31, 32 and 33 is journaled in a respective one of the cross-shaped openings 16 in the guide forming means 13, 12 and 11 by the bolts 22 and 26. Each of the three sets of guiding and forming rollers 31, 32 and 33 includes a first pair of guide-forming rollers 34, 35 and 36, respectively. Each roller of the first pair of guide-forming rollers 34, 35 and 36 is substantially identical to any of the other rollers and differs therefrom only in the convex curvature thereof. That is, the rollers of the first pair of guide-forming rollers 34 are less convexly curved than the rollers of the first pair of guide-forming rollers 35 or 36. Thus, the convex curvature of the first pair of guide-forming rollers 34, 35 and 36 progressively increases from left to right as shown in FIGURE 2, thereby defining a generally converging predetermined path.

Each of the three sets of opposed convexly curved guiding and forming rollers 31, 32 and 33 includes a second pair of concave guide-forming rollers 37, 38 and 39, respectively. Each roller of the second pair of guide-forming rollers 37, 38 and 39 is identical to any of the other rollers of the second pair of guide-forming rollers except for differences in the concave curvature thereof.

Since the sets of guiding and forming rollers 31, 32 and 33 are substantially identical, a description of the pair 33 shown in FIGURE 3 is believed sufficient to enable one skilled in the art to practice this invention. As was heretofore noted, the sets of guiding and forming rollers 33 includes a first pair of guide-forming rollers 36. The first pair of guide-forming rollers 36 includes two identical rollers 40 which are axially apertured at 41. Each of the rollers 40 includes an axially extending convexly curved peripheral groove 42 presenting inwardly directed opposed convex surfaces 43. End portions 44 of the rollers 40 are identically contoured to present inwardly directed opposed concave surfaces 45. A conveyor belt 47 is entrained over each of the rollers 40 and confined within the grooves 42 thereof. Each of the conveyor belts 47 extends the length of the reforming apparatus 10 and converge from left to right as viewed in FIGURE 1. Innermost runs 48 of the conveyor belts 47 intimately abut the convex opposing surfaces 43 of the rollers 40, and present a smooth, uninterrupted surface between the ends 44 of each of the rollers 40. The conveyor belts 47 are driven in a direction indicated by the arrows shown in

FIGURE 1 by a driving mechanism DM which will be more fully described hereafter.

A roller 49 is journalled within each of the downwardly and upwardly opening portions 17 and 18, respectively, of the cross-shaped opening 16. The rollers 49, 49 make up the second pair of guide-forming rollers 39 hereinbefore mentioned. Each of the rollers 49 is axially apertured at 50 and thus journalled upon a respective one of the bolts 22. An annular groove 51 in each of the rollers 49 has an identical conveyor belt 53 entrained thereabout.

Innermost conveyor belt runs 54 of the conveyor belts 53 are driven in a direction indicated by the arrows in FIGURE 1, and similarly converge along the length of the reforming apparatus 10. The direction of movement of the conveyor belt runs 48 and 54, as well as the linear velocity thereof, is identical. The conveyor belts 47 and 53 thereby cooperate to form a transport mechanism for transporting can bodies the entire length of the forming apparatus 10.

The rollers 40 and 49 are arranged in the cross-shaped opening 16 of the guide block 15 to form an axially accessible opening O of a generally hour-glass contour, as is best illustrated in FIGURE 3. The other two sets of opposed convexly curved guiding and forming rollers 31 and 32 journalled in the guide-forming means 13 and 12, respectively, are similarly arranged in a generally hour-glass contour. Thus, the three sets of opposed convexly curved guiding and forming rollers 31, 32 and 33 cooperate to define a longitudinally extending, axially open path through which can bodies, such as the can body C, may be transported by the conveyer belts 47 and 53. In addition, because the convex curvature of the sets of guiding and forming rollers 31, 32 and 33 progressively increases, as is best shown in FIGURE 2, the longitudinally extending hour-glass opening O converges from left to right as viewed in FIGURES 1 and 2.

Thus, after a can body has been initially formed on a conventional round or hour-glass mandrel of a body making machine, the ellipsoidal can body is transported (by means not shown) to the reforming apparatus 10 and enters the apparatus 10 between the least convexly curved set of opposed guiding and forming rollers 31. The conveyor belt runs 48 and 54 draws the can body into the hour-glass opening O formed by the rollers 31. The slight convex curvature of the guiding and forming rollers 31 causes portions of the ellipsoidal can body to "neck-in" slightly and conform to the hour-glass contour of the opening O thereof. As the innermost runs 48 and 54 of the conveyor belts 47 and 53 transport the can body progressively through the guide-forming means 12 and 11, the necked-in portions or sides of the can body are further indented because of the increased convex curvature of the guiding and forming rollers 32 and 33 until the can body is formed to the hour-glass cross-sectional configuration illustrated in FIGURE 3. Inasmuch as a can body, such as the can body C shown in FIGURE 3, is supported only on the exterior thereof during its travel with the conveyor belts 47 and 53, the rounded corners and side panels thereof are overbent or indented to compensate for over-recovery of the side panels. That is, the openings O allow the can body C to be indented or necked-in in an unrestricted manner and consequently, the convex curvature of the forming rollers 31, 32 and 33 can be increased to an extent necessary so that the return positions of the side panels of an "F" style can body made from thinner, higher tempered tin-plate will lie within required limits and maintain cross-sectional configuration illustrated in solid lines in FIGURE 8.

It is also important to note that the height of the can body is progressively reduced as it progresses through the reforming apparatus 10 due to the "necking-in" of the can body while reforming the same to the hour-glass contour. Furthermore, the corners of the can body are increased in curvature during the "necking-in" of the can body. These conditions are comparatively illustrated in FIG-

URE 8 of the drawings. The finally reformed can body C in solid lines has a corner radius of .595 inch while the corner radius prior to removal from the reforming apparatus is .412 inch. The table below lists various dimensions of the hour-glass contoured can body C in phantom lines in FIGURE 8 prior to removal from the reforming apparatus 10, and serves to illustrate appreciable reformation of the can body C made possible by the reforming apparatus 10 because of the absence therein of a forming horn or mandrel.

TABLE I

	Circular Corner Arc		Parabolic Panel Arc		Flat Panel
	R	A	L	H	CL
Last Reforming Station.....	.412"	180°	2.394"	.446"	.464"

In FIGURE 6 there is shown a reforming or deforming apparatus comprising a guide-forming means 60. Additional guide-forming means (not shown) are maintained in spaced relation and axial alignment with the guide-forming means 60 by a plurality of supports 61, in the manner clearly illustrated in FIGURE 1 of the drawings. The guide-forming means 60 includes a guide block 62 having a generally cross-shaped opening 63. A concave curved guiding and forming roller 64 is journalled in a downwardly opening portion 65 of the cross-shaped opening 63 by means of a threaded bolt 66 in a manner clearly illustrated in FIGURE 5. Similarly, an identical concavely curved guiding and forming roller 64 is journalled on an identical threaded bolt 66 in an upwardly opening portion 67 of the cross-shaped opening 63. An annular groove 68 is provided in each of the rollers 64. Entrained about each of the rollers 64 and retained within the grooves 68 is an identical conveyor belt 71. Inner most conveyor belt runs 72 of the conveyor belts 71 are adapted to move a can body therewith in the same manner and direction as the conveyor belt runs 54 illustrated in FIGURE 2.

The cross-shaped opening 63 also includes a pair of inwardly opening portions 73. An identical threaded bolt 74 traverses each of the openings 73, and is threadably secured in the guide block 62 in a manner identical to the attachment of the bolts 26 in the guide block 15. Two identical rollers 75 are journalled on each bolt 74 and have a concave periphery. The rollers are retained by suitable means (not shown) in spaced relation to each other and in opposed relation to the rollers on the other bolt 74. The guiding and forming rollers 64 and 75, and the conveyor belt runs 72 are cooperatively arranged to form an axially accessible opening O. It should be noted that only the rollers 64 and 75 cooperate to reform the can body C and the necking-in of the side panels thereof is caused by the rollers 75 engaging and reforming only the rounded corners of the can body C. Unrestricted overbending of the rounded corners of the can body C to compensate for over-recovery of the side panels of the can body C is accomplished by again supporting the can body C only on the exterior thereof during its travel with the conveyor belt runs 72. Consequently, the concave curvature of the rollers 75 can be increased to an extent necessary to allow the side panels of an "F" style can body to recover from the hour-glass cross-sectional configuration illustrated in phantom lines in FIGURE 6 to the cross-sectional configuration illustrated in FIGURE 8.

Another reforming or deforming apparatus is shown in FIGURE 7 of the drawings and is generally designated by the reference numeral 80. The reforming apparatus 80 includes a plurality of guide-forming means 81. The guide-forming means 81 comprise a plurality of longitudinally extending cylindrical rods. The plurality of longitudinally extending rods are arranged to form a frame or cage 82 of a generally hour-glass cross-sectional configuration. The spaced rods 81 of the cage 80 are con-

toured longitudinally so that the reformation of a can body C will be completed when the can body C leaves the cage 80. That is, a gradual progressively necking-in of the can body C will result when the can body C is transported from an open entrance end (not shown) of the cage 82 to an open exit end 83 thereof.

Can bodies are transported through the cage 82 by a first pair of opposed conveyor belt runs 84 and a second pair of opposed conveyor belt runs 85. The conveyor belt runs 84 and 85 extend the entire longitudinal extent of the cage 82 and are driven in the direction of the arrows by a drive mechanism which is not shown. Each of the conveyor belt runs 85 is inwardly convexly bowed and retained in the bowed condition by a plurality of rods 87 of the plurality of longitudinally extending cylindrical rods 81. In this manner, the cage 82 forms an axially accessible hour-glass contoured opening O and cooperates with the conveyor belt runs 84 and 85 to progressively exteriorly reform the can body C to compensate for over-recovery of the side panels thereof. By solely supporting the exteriors of can bodies being transported through the cage 82, the convex curvature of the cage 82 can be increased to an extent whereby highly tempered, thin can bodies will return from the reformed position shown in phantom lines in FIGURE 8 to the "F" style contour illustrated therein in solid lines.

As has been heretofore noted in connection with FIGURES 1 through 4 of the drawings, the innermost conveyor belt runs 54 of the conveyor belts 53 are moved by a drive mechanism DM in the direction indicated by the arrows of FIGURE 1. The drive or driving mechanism DM includes a substantially rectangular drive roller support 90 secured to each of the supports 14 by suitable means (not shown) between the guide-forming means 11 and 12 of the reforming apparatus 10. The substantially rectangular drive roller support 90 includes a pair of upstanding parallel side walls 91 and 92. A drive roller 93 having a shaft 94 secured thereto is journaled by suitable bearings 95 between identical apertures 96 in an uppermost portion of the respective side walls 91 and 92. As is best illustrated in FIGURE 5 of the drawings, a drive sprocket 97 is secured to the shaft 94 of the drive roller 93.

An identical elongated, vertical slot 98 is formed in each of the side walls 91 and 92 directly below the apertures 96. An idler roller 99 having a shaft 100 is journaled between the side walls 91 and 92 of the roller support 90 by the elongated slots 98. An identical biasing spring 101 in each of the elongated slots 98 urges the idler roller 99 toward the drive roller 93. The uppermost conveyor belt run of the conveyor belt 53 is positioned between the rollers 93 and 99 and thereby frictionally driven from right-to-left in FIGURE 2 of the drawings.

A roller 102 including a shaft 103 and a drive sprocket 104, identical to the drive roller 93, the shaft 94 and the drive sprocket 97 is mounted between lower portions of the side walls 91 and 92 in a manner substantially identical to that illustrated in FIGURE 5 of the drawings. Likewise, an idler roller 105 having a shaft 106 is biasingly journaled in a pair of identical elongated slots 107 by each of two identical compression springs 108, again in a manner identical to that clearly shown in FIGURE 5 of the drawings and a discussion of which is deemed unnecessary.

As is best shown in FIGURE 3 of the drawings, a motor M is supported adjacent the side wall 92 of the drive mechanism DM by any suitable means (not shown). The motor M includes an output shaft 109 to which is secured a sprocket 110. A drive chain 111 is entrained about the sprockets 97, 104, and 110.

As the sprocket 110 of the motor M rotates in a clockwise direction, as viewed in FIGURE 2 of the drawings, the drive roller 93 is rotated in a clockwise direction causing left-to-right movement of the lower conveyor belt run 54 of the top conveyor belt 53. This same clockwise rotation of the sprocket 110 drives the sprocket 104 and the

drive roller 102 in a clockwise direction imparting left-to-right motion to the conveyor belt run 54 of the lower conveyor belt 53 of FIGURE 2. Thus, a plurality of can bodies may be transported from left-to-right as viewed in FIGURES 1 and 2 of the drawings through the reforming mechanism 10 by the opposed conveyor belt runs 54 of the conveyor belt 53. Since the drive rollers 93 and 102 drive the outermost conveyor belt runs of the conveyor belts 53 and in non-interfering spaced relationship with respect to the innermost conveyor belt runs 54 of the opposed conveyor belts 53, a can body is supported solely exteriorly thereof when transported by the innermost conveyor belt runs 54.

While various forms of reforming or deforming structures have been disclosed herein, it is to be understood that various modifications thereof would be apparent and are within the scope of this invention. For example, the longitudinally extending rods 87 of the cage 82 shown in FIGURE 7 could be omitted if considered necessary or desirable, and the remaining rods located at the rounded corners of the can body C would cause the side panels thereof to concavely neck-in during the reforming operation. Similarly the rods at the corners of the can body C could be replaced by a plurality of solid arcuately-shaped longitudinally extending converging bars or the cage 82 could be constructed as an entirely peripherally closed, elongated, tapered tubular member.

It is also conceivable that the "F" style can bodies may be preformed into cylindrical shape on a cylindrical mandrel of a body making machine instead of into an ellipsoidal shape on an "hour-glass" mandrel.

If only minor reformation of can bodies is required, it may be accomplished by feeding the can bodies between a single guide-forming means, such as the guide-forming means 11, 12 or 13 shown in FIGURE 1.

While example disclosures of different types of reforming apparatus for forming "F" style can bodies are shown herein, it is to be understood that changes in the disclosed structures and arrangements may be made without departing from the spirit and scope of the invention as defined in the appended claims.

What is claimed is:

1. Apparatus for deforming substantially hollow cylindrical flexible metallic bodies into "F" style can bodies comprising a generally elongated support, means defining a predetermined path of travel for cylindrical bodies through said support, said path defining means including transport means for transporting cylindrical bodies interiorly of and through said support along said predetermined path, means for shaping the cylindrical bodies to a generally hour-glass transverse cross-sectional configuration without imparting a permanent set to the can bodies whereby the can bodies can rebound to a generally rectangular transverse cross-sectional configuration after departing said predetermined path, said predetermined path being a completely opened elongated area devoid of auxiliary forming mechanisms, and said shaping means comprising the sole means for shaping the cylindrical bodies to the hour-glass cross-sectional configuration thereof.

2. Apparatus for deforming substantially hollow cylindrical bodies into "F" style can bodies comprising a transport mechanism defining a predetermined path of travel for said cylindrical bodies, guide-forming means cooperative with said transport mechanism for guiding and deforming the cylindrical bodies being transported by said transport mechanism, a plane through said guide-forming means and said transport mechanism transverse to said path of travel defining an open area of a generally hour-glass configuration whereby the can bodies are deformed by said guide-forming means to a generally hour-glass cross-sectional configuration, said guide-forming means being provided with surfaces enclosing portions of said open area and comprising the

sole means for deforming portions of the cylindrical bodies to a substantially hour-glass cross-sectional configuration.

3. The apparatus for deforming substantially hollow cylindrical bodies into "F" style can bodies as defined in claim 2 wherein said guide-forming means include a plurality of individual guide members disposed along said predetermined path.

4. The apparatus for deforming substantially hollow cylindrical bodies into "F" style can bodies as defined in claim 3 wherein said plurality of individual guide forming members enclose portions of said predetermined path.

5. Apparatus for deforming substantially hollow cylindrical bodies into "F" style can bodies comprising a transport mechanism defining a predetermined path of travel for said cylindrical bodies, guide-forming means cooperative with said transport mechanism for guiding and deforming the cylindrical bodies being transported by said transport mechanism, a plane through said guide-forming means and said transport mechanism transverse to said path of travel defining an open area of a generally hour-glass configuration whereby the can bodies are deformed by said guide-forming means to a generally hour-glass cross-sectional configuration, said guide-forming means being provided with surfaces enclosing portions of said open area and comprising the sole means for deforming portions of the cylindrical bodies to a substantially hour-glass cross-sectional configuration, said surfaces including at least two convexly opposed guide-forming surfaces whereby two opposed portions of cylindrical bodies transported by said transport mechanism are outward concavely deformed.

6. Apparatus for deforming substantially elliptical hollow resilient bodies into "F" style can bodies comprising a transport mechanism, said transport mechanism including two opposed movable portions defining a predetermined path of travel for transporting said elliptical bodies therebetween, guide-forming means including at least two opposed convexly curved surfaces arranged at opposite sides of said predetermined path, a plane through said two opposed movable portions and the opposed convex surfaces transverse to said predetermined path defining an area of a generally hour-glass configuration whereby elliptical bodies transported to and deformed by said guide-forming means assume a substantially hour-glass cross-sectional configuration and upon inactivation of said guide-forming means recover to "F" style contoured can bodies.

7. The apparatus as defined in claim 6 wherein said two opposed movable portions comprise conveyor belt runs.

8. Apparatus for reforming substantially resilient tubular bodies into "F" style can bodies comprising a longitudinally extending axially accessible member having first and second open ends, said member including a transport mechanism defining a path of travel for tubular bodies between said first and second open ends, said member further including a plurality of guide-forming means disposed along said predetermined path, said guide-forming means including at least two opposed convexly curved surfaces at opposite sides of said predetermined path, a plane through said transport mechanism and said guide-forming means transverse to said predetermined path anywhere between said first and second ends defining an area of a generally hour-glass configuration whereby resilient tubular bodies are exteriorly reformed to a generally hour-glass cross-sectional configuration and upon removal from one of said ends recover to the contour of "F" style can bodies.

9. The apparatus as defined in claim 8 wherein the curvature of said opposed convexly curved surfaces increases from said first to second open end whereby the predetermined path is caused to converge between the ends of said member.

10. The apparatus as defined in claim 9 wherein said transport mechanism includes two opposed conveyor belt runs extending between the ends of the axially accessible member along said predetermined path, and a plurality of said opposed convexly curved surfaces are arranged to guidingly maintain said conveyor belt runs for movement along said predetermined path.

11. Apparatus for reforming the sides of resilient hollow tubular bodies to form "F" style cans comprising a transport mechanism for moving a plurality of tubular bodies along a predetermined path, guide-forming means on opposite sides of said predetermined path for deforming tubular bodies transported therebetween, said guide-forming means including a first pair of guide-forming rollers having convexly opposed surfaces effective to indent the resilient sides of tubular bodies to an outward concave shape, and means adjacent the convexly opposed surfaces and cooperative therewith to confine the reformed tubular bodies in a generally hour-glass cross-sectional configuration.

12. Apparatus for reforming the sides of resilient hollow tubular bodies to form "F" style cans comprising a transport mechanism for moving a plurality of tubular bodies along a predetermined path, guide-forming means on opposite sides of said predetermined path for reforming tubular bodies transported therebetween, said guide-forming means including a first pair of guide-forming rollers having convexly opposed surfaces effective to indent the resilient sides of tubular bodies to an outward concave shape, and means adjacent the convexly opposed surfaces and cooperative therewith to confine the reformed tubular bodies in a generally hour-glass cross-sectional configuration, said last mentioned means including a second opposed pair of guide-forming rollers, and a plane transverse to said predetermined path through said first and second pair of guide-forming rollers defining an area of a generally hour-glass configuration.

13. The apparatus as defined in claim 12 wherein said transport means includes at least one conveyor belt for transporting can bodies along said predetermined path.

14. The apparatus as defined in claim 12 wherein said second pair of guide-forming rollers has concavely opposing surfaces.

15. Apparatus for reforming the sides of resilient hollow tubular bodies to form "F" style cans comprising a transport mechanism for moving a plurality of tubular bodies along a predetermined path, guide-forming means on opposite sides of said predetermined path for reforming tubular bodies transported therebetween, said guide-forming means including a first pair of guide-forming rollers having convexly opposed surfaces effective to indent the resilient sides of tubular bodies to an outward concave shape, and means adjacent the convexly opposed surfaces and cooperative therewith to confine the reformed tubular bodies in a generally hour-glass cross-sectional configuration, said last mentioned means and the air of guide-forming rollers providing the sole means for reforming said can body.

16. The apparatus as defined in claim 15 wherein first additional pairs of said first pair of guide-forming rollers are provided in alignment therewith and arranged on opposite sides of said predetermined path, each of said first additional pairs of guide-forming rollers having convexly opposed surfaces, the convex curvature of each of said first additional pairs of guide-forming rollers differing from any of the others of said first additional pairs and from the said first pair of guide-forming rollers.

17. The apparatus as defined in claim 16 wherein the different convex curvature of said rollers causes said predetermined path to converge lengthwise thereof.

18. The apparatus as defined in claim 17 wherein said last mentioned means comprises second additional opposed pairs of rollers, each roller of said second additional opposed pairs of rollers being adjacent each roller of said first additional pairs of rollers, thereby forming a

plurality of longitudinally disposed pairs of rollers, a plane through each of said longitudinally spaced pairs of rollers defining a generally hour-glass shaped open area.

19. The apparatus as defined in claim 18 wherein means are provided on said plurality of rollers, said transport mechanism comprising a plurality of conveyor belt runs, each of said conveyor belt runs being adapted to drive said rollers through said means on said plurality of rollers.

20. The apparatus as defined in claim 19 wherein the means on said plurality of rollers are peripheral grooves adapted to confine the conveyor belt runs therein.

21. An apparatus for reforming the sides of resilient tubular bodies to form "F" style cans comprising a longitudinally extending axially open guide-forming means, a transport mechanism for transporting can bodies through said guide-forming means, the cross-sectional configuration of said guide-forming means being of a generally hour-glass configuration, said guide-forming means solely outward-concavely indenting the sides of resilient hollow tubular bodies.

22. The apparatus as defined in claim 21 wherein said longitudinally extending guide-forming means comprise a plurality of rods.

23. The apparatus as defined in claim 21 wherein said transport mechanism includes at least one conveyor belt run.

24. The apparatus as defined in claim 21 wherein said transport mechanism includes a plurality of conveyor belt runs, each run being confined within said guide-forming means.

25. An apparatus for deforming longitudinal edges of resilient hollow tubular bodies to form "F" style cans including a transport mechanism defining a predetermined path and guide-forming means, said transport mechanism being adapted to transport can bodies to and beyond said guide-forming means, said guide-forming means including first and second concavely opposed pairs of surfaces and each of said concavely opposed surfaces concavely opening toward a single vertical plane longitudinally of said predetermined path.

26. The apparatus of claim 25 wherein means are provided between each of said first and second concavely opposed pairs of surfaces and cooperative therewith to deform the longitudinal edges of a resilient can body thereby deforming the can body to a generally hour-glass cross-sectional configuration.

27. The apparatus of claim 26 wherein said guide-forming means and said last mentioned means are guide-forming rollers.

28. The apparatus of claim 27 wherein said transport means includes at least a first conveyor belt run cooperative with a guide-forming roller of said last mentioned means and at least a second conveyor belt run adjacent said first mentioned conveyor belt run and cooperative therewith.

29. A method of producing "F" style can bodies from a tubular resilient body comprising the steps of indenting opposite sides of the tubular body while maintaining the hollow interior of the tubular body free from internal forming means, terminating the indenting when the indented portions are concave outwardly, and releasing the indented portions and permitting the same to reshape themselves by outward springing from the indented concave form to a flat planar form.

30. A method of producing "F" style can bodies with polygonal sides from a resilient tubular body comprising the steps of indenting opposite sides of the tubular body while maintaining the hollow interior of the tubular body free from internal forming means, detaining other portions of the tubular body against movement from the axis of the tubular body, terminating the indenting when the indented portions are concave outwardly, and releasing the indented portions and permitting the same to reshape themselves by outward springing from the indented concave form to a flat planar form.

31. A method of producing "F" style can bodies with polygonal sides from a hollow tubular body of a generally elliptical cross-sectional configuration comprising the steps of exteriorly indenting opposite sides of the tubular body while detaining adjacent sides of said body against movement, and releasing the indented sides and permitting the same to reshape themselves by outward springing from the indented concave form to a flat planar form.

32. A method of producing "F" style can bodies with polygonal sides from a sheet metal can-blank comprising the steps of forming a flat blank to an hour-glass contour on a mandrel of a can body making machine, removing the formed body from the mandrel causing the body to reform to a generally elliptical cross-sectional configuration, exteriorly indenting portions of the body while detaining other portions thereof against movement to deform the body to an hour-glass contour and subsequently permitting the body to reshape itself by outward springing to a polygonally sided body.

33. An apparatus for reforming the sides of resilient tubular bodies to form "F" style cans comprising a longitudinally extending axially open guide-forming means, a transport mechanism for transporting can bodies through said guide-forming means, the cross-sectional configuration of said guide-forming means being of a generally hour-glass configuration, said guide-forming means solely outward-concavely indenting the sides of resilient hollow tubular bodies, said longitudinally extending guide-forming means being a tubular member having an open entrance end and an open exit end, and said tubular member converging from said open entrance end to said open exit end to thereby define a generally axially accessible hour-glass contoured converging passage.

34. The apparatus as defined in claim 33 wherein said transport mechanism includes at least one conveyor belt run.

35. The apparatus as defined in claim 33 wherein said transport mechanism includes a plurality of conveyor belt runs, each run being confined within said converging tubular member.
